SPRAY GUN

Frank H. Richterkessing, Louisville, Ky., assignor
to W. M. Cissell Manufacturing Co., Inc., Louisville, Ky., a corporation of Kentucky

Application November 7, 1944, Serial No. 562,330

3 Claims. (Cl. 251—134)

1

This invention relates to improvements in water spray-guns, and has particular reference to valve constructions for the control of fluid pressure.

The primary object of this invention is to provide a spray gun suitable for moistening fabrics, clothes, etc., in laundries and dry-cleaning establishments.

Another object of the invention is to provide a valve construction of the packless type having a diaphragm for sealing the valve chamber, and a hollow valve-stem through which the fluid medium is conducted into the valve chamber.

A further object of the invention is to provide a valve construction that is sturdy, and simple to manufacture and maintain.

The advantages of these and other objects will become apparent as the following description is read in connection with the accompanying drawings in which:

Figure 1 is a side elevational view of one embodiment of the invention;

Figure 2 is a front elevational view of Figure 1; Figure 3 is a sectional view taken along line 3—3 of Figure 1 showing the pivot pin 3 for the actuating lever 2, and the hollow stem 4;

Figure 4 is a sectional view taken along line 4—4 of Figure 1 showing the handle grip 1G and actuating lever 2;

Figure 5 is a partial sectional view taken along line 5—5 of Figure 2;

Figure 6 is an enlarged side elevational sectional view of the valve assembly of Figure 1, showing the diaphragm 14 and the construction and relation of the parts within the valve chamber;

Figure 7 is a side elevational view of another embodiment of my invention;

Figure 8 is a sectional view taken along line 8—8 of Figure 7;

Figure 9 is a sectional view taken along line 9—9 of Figure 7;

Figure 10 is a sectional view taken along line 10—10 of Figure 7;

Figure 11 is an enlarged side elevational sectional view of the hose connection of Figure 7 showing the connector 6 and the guide 4D for the hollow stem 4;

Figure 12 is an enlarged side elevational sectional view of the valve assembly of Figure 7 showing the diaphragm 14 and the construction and relation of the parts within the valve chamber.

In the drawings, Figures 1 to 6 inclusive, illustrate one embodiment of the invention, while Figures 7 to 12, inclusive, show another embodiment.

2

ment of the invention, and in order to facilitate the identity of similar parts in each embodiment, like reference characters and numerals are employed to identify similar parts.

With reference to the drawings, it will be apparent that the one embodiment of the invention shown in Figures 1 to 6 is characterized by a construction having a conventional pistol grip in which the fluid is discharged substantially at right angles to the grip, while the other embodiment shown in Figures 7 to 12 is characterized by a construction having a conventional squeeze grip in which the fluid is discharged substantially parallel to the grip.

15 The valve assembly of each embodiment is identical, and this will be evident from a comparison of Figures 6 and 12. Likewise, the hose connection in each embodiment is identical, and this will also be apparent from a comparison of

20 the left hand portion of Figure 5 with Figure 11.

The actuating lever of each embodiment is also quite similar in construction inasmuch as each lever is preferably a stamping having two arms 2A with cam type actuating surfaces 2B that engage annular rings 4B on a hollow plunger 4. Likewise, each lever is pivotally mounted within a housing 1 by a suitable bearing pin 3.

25 The embodiment shown in Figures 1 to 6 employs a compression spring 16 for operating the valve assembly to a closed condition, while the embodiment shown in Figures 7 to 12 employs a tension spring 19. Otherwise, except for the difference in construction of the housings, each embodiment is quite similar, and for a detail description thereof reference is first made to Figures 1 to 6.

In Figure 1, the numeral 1 designates a housing having a grip portion 1G and an eye 1H for hanging the gun when the same is not in use.

As shown in Figures 1 and 3, the actuating lever 2 is preferably a sheet-metal stamping having two arms 2A straddling a hollow plunger 4. Each arm 2A has a pair of cam-type actuating surfaces 2B that engage annular rings 4B carried by the hollow plunger 4, and each arm is pivotally mounted within the housing 1 upon a suitable bearing-pin 3 that is threaded into one wall of the housing 1.

30 As shown in Figures 1, 2 and 4 the actuating lever 2 is constructed to move into the housing 1 when the same is actuated to open the valve. As shown in Figure 1, a compression spring 16 reacts between the lever 2 and a shouldered adjusting-screw 15, to bias the valve to its closed

condition. The adjusting screw 15 is threaded into the housing 1 so that the screw may be adjusted to regulate the closing pressure upon the valve.

As shown in Figures 1 and 5, the hollow plunger 4 terminates at its rear end in a spherical guide 4S having a threaded neck 4E extending diagonally upwardly therefrom. A flanged hose connection is detachably secured to the threaded neck 4E by means of a threaded cap 5.

As indicated in Figure 1, the top of the housing 1 is slotted at the rear end thereof, and the reduced cylindrical portion of the threaded neck 4E reciprocates therein to prevent the plunger 4 from being rotated about its longitudinal axis.

As shown in Figure 5 the hose connection 6 has a hollow bore 6A communicating with a hollow bore 4A in the plunger 4, and, as shown in Figures 5 and 6, the plunger 4 has a cylindrical guide 4G journaled in a cylindrical bore formed in an externally threaded boss 1N of the housing 1 so that it will reciprocate therein when the lever 2 is actuated.

As shown in Figure 6, the guide 4G of the plunger 4 has a valve stem 12 threaded into the forward end thereof. A diaphragm 14, preferably made of rubber, serves to seal the valve chamber, and this diaphragm is detachably secured at its central portion between the end of the guide 4G and the hexagon portion of the valve stem 12. A washer 13 is provided between the hexagon portion of the valve stem 12 and the diaphragm 14 to prevent damage to the diaphragm when the assembly is tightened.

The diaphragm 14 is detachably secured at its periphery between the end of the threaded boss 1N of the housing 1, and the flanged end 8A of the valve bonnet 8.

As shown in Figure 6, the flanged end 8A of the valve bonnet 8 is detachably secured to the threaded boss 1N of the housing 1 by means of a threaded sleeve 7. The inwardly extending flange on sleeve 7 engages the outwardly extending flange 8A on bonnet 8.

The valve bonnet 8 has a threaded end 8B to which is detachably secured a threaded cap 9 having a discharge aperture 9A. A renewable valve seat 10, consisting of a thin washer having a small discharge orifice 10A, is located within the cap 9, and is detachably secured to the end 8B of the valve bonnet 8 by means of the cap 9. A gasket 11 seals the valve seat 10 to the end 8B of the valve bonnet 8.

The outer end of the valve stem 12 is provided with a slightly enlarged guide 12A that is slidably journaled in the bore 8D of the valve bonnet 8. The guide 12A is also provided with diagonal slots 12B cut in the cylindrical surface thereof, to break the fluid into a fine mist.

As shown in Figure 6, the guide 12A is slidably mounted within the bore 8D of the valve bonnet 8, and the hexagon portion of the valve stem 12 operates within the chamber 8C of the bonnet.

The valve stem 12 is provided with a hollow bore 12C communicating with the hollow bore 4A of the plunger 4. The valve stem 12 is also provided with transverse openings 12D communicating with the bore 12C.

Accordingly, with reference to Figures 5 and 6, fluid entering bore 6A of the hose connection 6, travels forwardly through the bore 4A of plunger 4 into the bore 12C of stem 12 and thence through the openings 12D into chamber 8C of bonnet 8.

A washer 12W, preferably made from a phenol-

aldehyde product, is fixedly secured in the forward end of the valve stem 12, which washer seals the small discharge orifice 10A in the valve seat 12 to provide the closed condition for the valve.

When the grip 1G and lever 2 is squeezed by an operator, the cam surfaces 2B of the lever 2 press against the corresponding ring 4B and move the hollow plunger 4 rearwardly. The valve stem 12 also moves rearwardly with the plunger 4, and the fluid flowing through the bores 6A, 4A and 12C discharges into the chamber 8C of the valve bonnet 8 via opening 12D, thence through the bore 8D, diagonal slots 12B, and the small discharge orifice 10A into atmosphere in the form of an extremely fine mist. When the lever 2 is released, the spring 16 recloses the valve by moving the washer 12W into sealing relation with the orifice 10A.

From the foregoing, it will be apparent that the bores 6A, 4A and 12C, and the transverse openings 12D provide a direct communication for the fluid flowing into the valve chamber, and greatly simplify manufacture and maintenance of the valve assembly.

In the operation of water-spray guns in laundries and dry cleaning establishments, it is customary to install a chamber in the steam supply line to collect water of condensation therefrom, and to extend a flexible hose from the lower end of the chamber to the hose connection 6 of the spray gun, to conduct condensation to the gun under the pressure of the steam flowing in the steam supply line.

Experience has shown this to be the preferred manner of operating water-spray guns as it eliminates entirely liming-over and clogging that is ordinarily encountered when spray guns receive water from domestic water lines.

On the other hand, it is to be understood that the features disclosed herein are applicable to spray guns operated on fluids other than the condensation specifically mentioned herein.

For a detailed description of the other embodiment of the invention disclosed herein, reference is made to Figures 7 to 12.

In Figure 7, the numeral 1 designates a housing having a grip portion 1G. Guns of the squeeze type are customarily employed to moisten articles on a horizontal surface, and therefore usually hang vertically above the surface from a spring attached to the hose, while guns of the pistol-grip type are customarily employed to moisten articles hanging in a vertical position.

As shown in Figures 7 and 9, the actuating lever 2 is preferably a sheet-metal stamping having two arms 2A straddling a hollow plunger 4. Each arm 2A has a pair of cam-type actuating surfaces 2B that engage an annular ring 4B and

the end of the square guide 4D carried by the hollow plunger 4. Each arm is pivotally mounted within the housing 1 upon a suitable bearing-pin 3 that is threaded into one wall of the housing 1.

As shown in Figures 7 and 9, the actuating lever 2 is constructed to move into the housing 1, when the same is actuated to open the valve. As shown in Figure 7, a tension spring 19 is secured to the lever 2 at 17 and to the housing 1 at 18, to bias the valve to its closed condition.

As shown in Figures 7, 8 and 11, the hollow plunger 4 has, near its rear end, a square guide 4D having a rearwardly-extending threaded shank 4E. A flanged hose connection is detachably secured to the threaded shank 4E by means of a threaded cap 5.

As shown in Figures 8 and 11, the square guide 4D is slidably journaled in a square opening 1D in the housing 1, to prevent the plunger 4 from being rotated about its longitudinal axis.

As shown in Figure 11, the hose connection 6 has a hollow bore 6A communicating with hollow bore 4A in the plunger 4, and, as shown in Figures 7, 11 and 12, the plunger 4 has a cylindrical guide 4G slidably mounted in the boss portion 1N of the housing 1, so that it will reciprocate therein when the lever 2 is actuated.

As shown in Figure 12, the guide 4G of the plunger 4 has a valve stem 12 threaded into the forward end thereof. A diaphragm 14, preferably made from rubber, serves to seal the valve chamber, and this diaphragm is detachably secured at its central portion between the end of the guide 4G and the hexagon portion of the valve stem 12. A washer 13 is provided between the hexagon portion of the valve stem 12 and the diaphragm 14, to prevent damage to the diaphragm when the assembly is tightened.

The diaphragm 14 is detachably secured at its periphery between the end of the threaded boss 1N of the housing 1 and the flanged end 8A of the valve bonnet 8.

As shown in Figure 12, the flanged end 8A of the valve bonnet 8 is detachably secured to the threaded boss 1N of the housing 1 by means of a threaded sleeve 7.

The valve bonnet 8 has a threaded end 8B to which is detachably secured a threaded cap 9 having a discharge aperture 9A. A renewable valve seat 10, consisting of a thin washer having a small discharge orifice 10A, is located within the cap 9, and is detachably secured to the end 8B of the valve bonnet 8 by means of cap 9. A gasket 11 seals the valve seat 10 to the end 8B of the valve bonnet 8.

The outer end of the valve stem 12 is provided with a slightly enlarged guide 12A that is slidably journaled in the bore 8D of the valve bonnet 8. The guide 12A is also provided with diagonal slots 12B cut in the cylindrical surface thereof, to break the fluid into a fine mist.

As shown in Figure 12, the guide 12A is slidably mounted within the bore 8D of the valve bonnet 8, and the hexagon portion of the valve stem 12 operates within the chamber 8C of the bonnet 8.

The valve stem 12 is provided with a hollow bore 12C communicating with the hollow bore 4A of the plunger 4. The valve stem 12 is also provided with transverse openings 12D communicating with the bore 12C.

Accordingly, with reference to Figures 7, 11 and 12, it will be seen that fluid entering bore 6A of the hose connection 6 travels forwardly through the bore 4A of plunger 4 into bore 12C of stem 12, and thence through the openings 12D into the chamber 8C of bonnet 8.

A washer 12W, preferably made from a phenol-aldehyde product, is fixedly secured in the forward end of the valve stem 12, which washer seals the small discharge orifice 10A in the valve seat 12 to provide the closed condition for the valve.

When the grip 1G and lever 2 is squeezed by an operator, the cam surfaces 2B of lever 2 press against the end of the square guide 4D and move the hollow plunger 4 rearwardly. The valve stem 12 also moves rearwardly with the stem 4, and the fluid flowing through the bores 6A, 4A and 12C discharge into chamber 8C of valve bonnet 8 via openings 12D, thence through the bore 8D,

diagonal slots 12B and the small discharge orifice 10A into atmosphere in the form of an extremely fine mist. When the lever 2 is released, the tension spring 19 biases the valve to its closed condition.

From the foregoing it will be apparent that the hollow plunger 4 provides a direct communication for the fluid from the bore 6A of hose connection 6 through the bore 12C and openings 12D into the valve chamber, and that this construction, along with the construction of the valve assembly, is identical in both embodiments shown in the accompanying drawings.

Having thus described the invention, I claim:

15. 1. A valve structure comprising a body member adapted to be held by the hand, and having an externally threaded boss extending outwardly therefrom; a cylindrical valve casing having a cylindrical valve cavity and an outwardly extending cylindrical flange on one end thereof; an internally threaded sleeve threaded upon the threaded boss and having an inwardly extending flange engaging the flange of the casing and securing the same to the end of the threaded boss; an internally threaded valve cap closed at one end by a wall having a discharge opening therein; the said valve casing having an externally threaded end receiving the internally threaded valve cap; a replaceable valve seat within said valve cap comprising an apertured disk clamped between the threaded end of said valve casing and the end wall of said cap, a valve stem positioned in the said valve cavity and mounted for reciprocation axially thereof to close and open the discharge opening, and a flexible disk having its peripheral portion clamped between said casing flange and the end of said boss and the central portion thereof sealed around said valve stem, said valve stem having an axial bore extending through the plane of said disk and opening through the side of the stem into said valve cavity.
2. A valve structure comprising a hollow body member having a grip portion adapted to be held by the hand, and having a longitudinal opening along one side thereof; a cylindrical casing having a cylindrical valve cavity and provided with an outwardly extending flange on one end thereof; an internally threaded sleeve slipped over the said casing and having an inwardly extending flange engaging the flange of the casing; the said body member having an externally threaded boss receiving the internally threaded sleeve for securing the casing to the body member; an internally threaded valve cap closed at one end by a wall having a discharge opening therein and a valve seat surrounding the opening; the said valve casing having an externally threaded end receiving the internally threaded cap for securing the valve seat axially in alignment with the cylindrical valve cavity; a valve stem slidably mounted in the hollow body member and extending into the valve cavity and mounted for reciprocation axially thereof to open and close the discharge opening; a flexible disk having its peripheral portion clamped between said casing flange and the end of said boss and the central portion thereof sealed around said valve stem, said valve stem having an axial bore extending through the plane of said disk and opening through the side of the stem into said valve cavity; an operating handle pivotally mounted within the hollow body member and having a free end portion thereof positioned in and extending lengthwise of the longitudinal opening in

the grip portion of said body member and adapted to be engaged by the hand; means connecting said handle with said valve stem for axially reciprocating the valve stem; and spring means mounted within the grip portion of said hollow body and acting on said handle to urge said valve stem against said valve seat.

3. A valve structure comprising a body member adapted to be held by the hand; an externally threaded boss extending outwardly from said body and having a cylindrical bore formed therein; a valve bonnet having a cylindrical valve cavity and provided with an outwardly extending circular flange on one end thereof; an internally threaded sleeve threaded upon said boss and having an inwardly extending flange engaging the flange of said bonnet and securing the same to the end of said boss with said valve cavity in axial alignment with the cylindrical bore of said boss; an internally threaded valve cap closed at one end by a wall having a discharge opening therein; said valve bonnet having an externally threaded forward end receiving the internally threaded valve cap; a replaceable valve seat within said valve cap comprising an apertured disk clamped between the forward end of said bonnet and the end wall of said cap, a hollow plunger having one end mounted in the cylindrical bore of said boss and the other end extending out of said body and adapted for connection to a source of fluid; a valve stem positioned in said valve cavity in axial alignment with said plunger and being secured to the end of said plunger by a threaded stem portion; said plunger and valve stem being mounted for recip-

rotation axially thereof to close and open the discharge opening in said valve cap; and a flexible disk having its peripheral portion clamped between said bonnet flange and the end of said boss and having an aperture at the center thereof, the portion of said disk surrounding said aperture being clamped between the abutting end faces of said plunger and said valve stem, whereby said disk seals the rear end of said valve cavity, and said valve stem having an axial bore extending from the rear end thereof through the plane of said disk and opening through the side of the stem into said valve cavity.
